UNITED STATES PATENT OFFICE.

WALTER R. CRIPPEN, OF CAMBRIDGE, MASSACHUSETTS, ASSIGNOR TO EMERSON PIANO COMPANY, OF BOSTON, MASSACHUSETTS, A CORPORATION OF ILLINOIS.

MUSIC-PLAYING INSTRUMENT.

No. 896,517.

Specification of Letters Patent.

Patented Aug. 18, 1908.

Application filed October 7, 1907. Serial No. 396,123.

To all whom it may concern:

Be it known that I, WALTER R. CRIPPEN, a citizen of the United States, residing at Cambridge, Middlesex county, Massachusetts, have invented certain new and useful Improvements in Music-Playing Instruments, of which the following is a full, clear, and exact description.

My invention relates to improvements in automatic musical instruments, and particularly to controlling means which may be employed for any useful purpose, for example for controlling pneumatic devices for securing expression effects.

The object of the invention is to provide a means whereby any one of several push buttons, adapted to be manually operated, may be employed for securing certain desired effects, which buttons may be, if desired, locked in their operative or active position. The arrangement is also such that the operation of one push button will release any of the other push buttons that may be locked.

In the drawings Figure 1 is a front elevation, partly in section, of my invention as it might be applied to an automatic music playing instrument. Fig. 2 is mainly a section on the plane of the line 2—5 of Fig. 4, of one button and associated parts. Fig. 3 is a plan view, looking down from the plane of line 3—3 of Fig. 1. Fig. 4 is a horizontal section on the line 4—4 of Fig. 1. Fig. 5 is a vertical section on the plane of the line 2—5 of Fig. 4, of several valves and channel board. Fig. 6 is a cross section on the plane of the line 6—6 of Fig. 1. Fig. 7 is a side elevation of a modified detail of construction.

A may represent the front board of an automatic music playing instrument.

B—B'—B²—B³ may represent four push buttons or devices for the manual operation of separate valves for the regulation of anything that may be desired, through the medium of ducts C—C'—C²—C³. These ducts are connected to duct extensions in a channel board D, which extensions lead, as later described, to the aforesaid valves indicated at E—E'—E²—E³. In the particular form shown, these valves are mounted upon stems 50 which connect with the aforesaid buttons respectively.

F is a shiftable locking bar through which there are a number of passages corresponding to the number of buttons employed. Fixed 55 on the valve stems respectively are what I

will term cones G—G'—G²—G³. These cones are preferably slightly smaller than the passages in bar F. Springs H may be employed to return the push buttons B—B'—B²—B³ to their inactive position. I is a spring tending to force this locking bar toward its locking position.

J is an adjustable head to limit the excursion of bar F toward its locking position.

In its normal position the locking bar stands as shown in Fig. 1, one side of each of the passages therein standing under the bevel of its respective cone. As shown in Fig. 4, it is preferred to have all the duct extensions lead to, and be controlled by, valve E. Three of said extensions lead to valve E', two to valve E² and one to valve E³.

The operation is as follows: If the button B is depressed partially, it will open the valve E. Whatever this valve is intended to control through ducts C to C³ will then be thrown into action, since all the ducts will be thereby opened. If it is desired to hold this button B down for any length of time, it is merely necessary to depress it fully or to such an extent that the cone G will pass through the locking bar F, whereupon the locking bar shifts instantly to the right under the action of spring I, so that the parts will assume the position indicated in Fig. 2, said locking bar 80 then overstanding the cone G, preventing it from rising. A different control may be effected by simply depressing another one of the buttons B' B² or B³. A full depression of the button B², for example, will not only 85 open valve E², but will also cast off the cone G, so that valve E will close. The control will then be effected through ducts C² C³ only. The partial depression of any of the buttons may be resorted to, if desired, without releasing any other valve that may be locked 90 open at that time.

While any one of the buttons B to B² may be employed to cast off any other one of the buttons that may be locked, an additional cast-off button and cone may be employed, if desired, which would merely serve to shift the locking bar F. This cast-off device might take the same form as any of the cones previously described, save that it might have a slight upward extension, such as indicated in Fig. 7, at G⁴ which might be substituted in place of the cone G³ of Fig. 1, for example. This upward extension would simply serve to prevent the locking down of this particular 105 110

cone, which in this event would merely perform the function of a cast-off and might or might not be provided with a valve. If, for example, such an apparatus were employed 5 for producing different dynamic effects, the valve E^3 might be employed to control pianissimo effect, E^2 to control piano effect, E' forte effect and E double forte effect. Assuming the composition to be rendered starts 10 with piano, the button B^2 would be fully depressed and locked. To shift to pianissimo merely requires the depression of the button B^3 , whereupon valve E^2 would be released and close while valve E^3 would be opened, 15 and so on. While I have shown certain ducts as extending to more than one valve, obviously each duct might extend to only its respective valve.

What I claim is:

- 20 1. In a device of the character described, two ducts, two valves, both of said ducts leading to one of said valves, one of said ducts

leading to the other valve, independent means for operating either of said valves independently, and means coöperating therewith to lock one of said operating means in a position to hold its valve open, said locking means being released by the operation of the other operating means. 25

2. In a device of the character described, 30 two ducts, two valves, both of said ducts leading to one of said valves, one of said ducts leading to the other valve, independent means for operating either of said valves independently, and means coöperating therewith to lock either of said operating means in a position to hold its valve open, said locking means being released by the operation of the other operating means. 35

WALTER R. CRIPPEN.
